UNITED STATES PATENT OFFICE.

RICHARD STUDDERT, OF WESTMINSTER, LONDON, ENGLAND.

MANUFACTURE OF TRAVELING-TRUNKS AND SIMILAR RECEPTACLES.

1,083,154.

Specification of Letters Patent. Patented Dec. 30, 1913.

Application filed February 15, 1913. Serial No. 748,508.

To all whom it may concern:

Be it known that I, RICHARD STUDDERT, a subject of the King of Great Britain, residing at Johnson Street Works, Victoria street, Westminster, in the county of London, England, have invented certain new and useful Improvements in or Relating to the Manufacture of Traveling-Trunks and Similar Receptacles, of which the following 10 is a specification.

This invention relates to the manufacture of traveling trunks and similar receptacles especially the kind ordinarily known as compressed cane trunks.

15 The object of the present invention is to effect economy in the manufacture of such receptacles to render their construction simpler and stronger and their appearance more slightly than heretofore.

20 According to the method heretofore generally adopted in manufacturing trunks of the kind above referred to, the cane strips have been attached to a canvas-like base and arranged so that they lie lengthwise with 25 respect to the trunk or receptacle under construction.

According to this invention cane strips are laid and secured, by glue or suitable adhesive, to a base composed of cane strips or 30 veneer in such a manner as to be situated at right angles or transversely to the said strips or the grain of the veneer of the said base, and the material, while the adhesive is in the wet condition, is placed in a mold or 35 about a former and pressed to shape and retained until it has dried and permanently set to the desired shape. A trunk or other receptacle thus made will present the advantage that the two halves thereof are each 40 made of a single piece of material which effectually retains its shape after formation.

In order that the said invention may be clearly understood and readily carried into effect I will describe the same more fully 45 with reference to the accompanying drawings, in which—

Figure 1 is a perspective view of a trunk constructed according to the present invention. Fig. 2 is a view showing the structure 50 of the material of which the trunk is made.

a' *a'* are the strips of cane which are arranged lengthwise of the trunk and constitute the aforesaid base.

b', *b'* are the transverse strips of cane

which are laid on and secured to the strips *a'* by an adhesive such as glue.

In constructing the material the cane strips *a'* and *b'* are made up in the form of a board on a foundation of paper or other material which can be afterward removed at 60

will, the sheets of cane being superimposed so that the cane strips *a'* run in a transverse direction to the strips *b'*. The two boards of cane having been secured to one another by glue or other adhesive are while the adhesive is in the wet condition placed in a

manner so as to retain them in their bent condition until the necessary shape has been obtained it being understood that the strips 70

a' of the base lie in the longitudinal direction of the mold and the superimposed cane strips *b'* transverse thereto. By arranging the two layers of cane strips in the manner set forth the tendency to distortion and 75

breaking away is obviated. The material having been removed from the mold, is applied to the trunk ends *c* which may be connected by battens of wood or other suitable material. The said ends of the trunk are 80

composed of wood of suitable thickness and are preferably formed of laminated veneer; laminated cane strips may however be employed. To obtain a flush surface between the battens and the ends of the receptacle, 85

the said battens are let into under-cut or dove-tailed recesses in the said ends. The said material having been thus applied to the trunk ends or battens it is secured in 90

place by the use of pins or other suitable fastenings. A covering of canvas *d* or the like is then applied to the aforesaid material and 95

may be japanned or painted or otherwise treated as desired; the canvas being secured in place by means of glue or other adhesive 95

and pins. An inner lining *d'* is also applied to the inner side of the cane material in the usual manner. Exterior battens *d'* may be provided and secured by pins which 100

pass through the same so as to enter and bind them to the corresponding interior battens when the same are employed, which connect the ends of the trunk, under the aforesaid cane material.

Instead of cane strips *a'* being employed, 105 as the base of the transversely arranged cane strips *b'*, the latter may be secured to a base of veneer laid with the grain at right angles

to the direction of the said strips *b'*. The base may, moreover, be constituted by material such as is employed at the present time when using the strips longitudinally of the trunk.

By constructing trunks as hereinbefore described great strength is imparted thereto; the ends being constructed of wood or laminated cane are considerably stronger and stiffer as compared with the ends of the usual trunks which are formed of a single layer of cane strips. The securing and weltting necessary in the usual construction are dispensed with; the ends in the improved trunk being secured by battens, pins and glue.

The improved method of manufacture is obviously applicable to the production of trunks, suit-cases and all kinds of receptacles for the use of travelers and for the conveyance of articles of apparel or otherwise.

What I claim and desire to secure by Letters Patent of the United States is:—

1. A method of manufacturing compressed cane trunks or other receptacles, consisting in laying and securing cane strips by suitable adhesive to a base composed of cane strips in such a manner as to be situated at right angles or transversely to the strips of said base, and placing the material, while the adhesive is in the wet condition in a molding device of fixed shape and pressing and retaining the same until it

has dried and permanently set to the desired shape.

2. A method of manufacturing compressed cane trunks or other receptacles consisting in laying and securing cane strips by suitable adhesive to a base composed of cane strips in such a manner as to be situated at right angles or transversely to the strips of the said base, and placing the material, while the adhesive is in the wet condition, in a molding device of fixed shape and pressing and retaining the same until it has dried and permanently set to the desired shape, and providing said body portion with wooden ends.

3. A method of manufacturing compressed cane trunks or other receptacles consisting in laying and securing cane strips by suitable adhesive to a base composed of cane strips in such a manner as to be situated across the strips of said base and placing the material while the adhesive is in the wet condition, against a molding device of fixed shape and pressing and retaining the same until it has dried and permanently set to the desired shape, and providing said body portion with laminated wooden ends.

In testimony whereof I affix my signature in presence of two witnesses.

RICHARD STUDDERT.
